PROCESS FOR PRODUCING ALKALI METAL SULPHIDES

Enzo Lanzetti, Como, Italy, assignor to Luigi Achille, Milan, Italy

Application April 15, 1936, Serial No. 74,592
In Italy June 15, 1935

5 Claims. (Cl. 23—134)

This invention relates to the production of alkali metal sulphides.

This new process consists in the reaction of the alkali-metal amalgams with an aqueous solution of the corresponding alkali-metal polysulphide.

According to this invention, the sodium sulphide, which usually is prepared by reduction of the sodium sulphate with carbon, is produced by reaction of sodium amalgam with aqueous solution of sodium polysulphide or a solution of sulphur in aqueous sodium sulphide.

The polysulphide may be prepared by reaction of sodium sulphide with sulphur and then reacted with the amalgam, or the solution of the sulphur in the sodium sulphide and the reaction with the amalgam are caused to take place at the same time.

The reaction forming the basis of the process may be represented as follows:

Or

Fundamentally the invention therefore resides in the synthesis of the sodium sulphide from sodium in the amalgam and elemental sulphur.

It is obvious that when the amount of alkali-metal of the amalgam does not correspond to that of the polysulphide used, mixtures of alkali metal sulphides are obtained.

Example 1

One of the well-known electrolyzers provided with a porous diaphragm may be employed, the electrolyte being a concentrated solution of common salt. During the electrolysis finely divided sulphur is brought to contact with the electrolyte consisting of sodium amalgam in the cathodic chamber only. The liquid in the cathodic chamber may be agitated by suitable means. During the operation the addition of the sulphur is controlled in such a way that the total sulphur content (S including Na_2S) in the electrolyte of the cathodic zone is maintained in such a manner that for the electric conductivity substantially the NaCl is decisive. The apparatus may be heated or cooled by suitable means. When continuing the electrolysis Na_2S is formed in the cathodic zone by the combination of the nascent alkali metal with sulphur, for instance, in the form of Na_2S_2 . The electrolytic reaction may be represented by the following formula:

It may be assumed that the following secondary reaction takes place:

From the solutions containing sodium sulphide and sodium chloride or in some cases sodium sulphide, sodium chloride and sodium hydroxide, the sodium sulphide may be separated by one of the well-known methods. The process as described may also be carried out continuously by correspondingly controlling the current intensity as well as the supply of the electrolyte and the sulphur.

Example 2

The apparatus used may be an electrolyzer provided with bell or an electrolyzer provided with a liquid diaphragm. The electrolyte may be a concentrated solution of potassium chloride. During the electrolysis the electrolyte is brought in the cathodic zone to contact with K_2S_2 dissolved, for instance, in water. During the operation the addition of K_2S_2 is controlled in such a way that the total sulphur concentration ($\text{S} + \text{K}_2\text{S}$) in the electrolyte of the cathodic zone is kept within such limits, that the KCl is decisive for the electric conductivity.

The apparatus may be heated or cooled. On continuing the electrolysis K_2S is obtained in the cathodic zone by the combination of K with K_2S_2 .

The electrolytic reaction may be expressed as follows:

The following secondary reaction is assumed to take place:

The process may be carried through continuously as in Example 1. The potassium sulphide may be separated from the resulting solutions by one of the well-known methods.

Example 3

An electrolytic apparatus of well-known construction having a moving mercury cathode may be employed. The electrolyte may be a concentrated solution of common salt. By the passage of the electric current a sodium amalgam of varying concentration according to the conditions chosen in each single case is formed. The transport of the sodium amalgam from the electrolytic to the reaction zone may be facilitated by stirring or other suitable means. When the amalgam in the reaction zone is brought to contact with the sulphur which may be loose or sus-

suspended in a suitable medium, for instance, water, Na_2S is formed by the reaction between the amalgam and the sulphur according to the following formula:

The following secondary reaction may take place:

Furthermore the following reaction might occur:

The contact between the amalgam and the sulphur may take place in the state of static equilibrium or may be intensified by stirring. The apparatus may be heated or cooled as required. The sodium sulphide may be separated from the solution or suspension by well-known methods. The process may also be carried through continuously.

Example 4

The decomposition of the amalgam may be effected in a separate apparatus. The latter may be of different type or shape (tube, channel or chamber) and may consist of metal or other suitable material. It may be provided with agitating means or not, and may further be provided with means for heating or cooling. The amalgam which is introduced into the apparatus continuously or intermittently may be of different concentration, for instance, it may contain 5 grams Na per 1000 grams Hg. The amalgam is brought to contact in the reaction apparatus with an aqueous solution of Na_2S_2 , the operation being controlled in such a way that during the contact between Hg and Na_2S_2 also HgNa is continuously present. In other terms the reaction takes place in continuous presence of HgNa , for instance, 0.6 gram of Na being present per 1000 grams of mercury. In this way I may attain that not HgS but Na_2S is formed by the combination of the amalgam with the polysulphide. The reaction may also proceed according to the following formulae:

or, as the case may be,

The following secondary reaction may occur:

The resulting amalgam may be returned, either immediately or after the remaining sodium has been removed by well-known methods, to circulate again in the electrolytic apparatus.

The process may also be carried out continuously. The sodium sulphide may be separated from the solution by well-known methods.

Example 5

The same apparatus as mentioned sub 4 may be employed. The sodium amalgam is brought to contact in the reaction apparatus, for instance, with an aqueous alcoholic solution of Na_2S_2 , care being taken that during the contact between the amalgam and the solution always activated $\text{S}(\text{Na}_2\text{S}_2)$ be continuously present. In this case I may avoid the formation of NaOH , only Na_2S being formed. The reaction may be expressed by the following equation:

As a secondary reaction the formation of HgS may take place according to the well-known formula. The process may be a continuous one.

Example 6

The same apparatus is employed as sub 4. In the reaction apparatus the sodium amalgam comes into contact, for instance, with an aqueous solution of Na_2S_4 . The process is conducted in such a way that both the conditions of Examples 10 4 and 5 are realized, i. e. the contact between the amalgam and the Na_2S_4 is accomplished in such a manner that sodium and activated sulphur are always present.

Furthermore the process is conducted in such a way that during the contact stoichiometric ratios exist between the amalgam and the Na_2S_4 to obtain a sodium sulphide of greatest purity.

By proceeding in this way the formation of NaOH and HgS may be avoided and a sodium sulphide of excellent purity may be obtained. This process too may be carried out continuously; the sodium sulphide may be separated by crystallisation or fusion.

To avoid the formation of mercury sulphide 25 during the reaction, the amalgam should be slightly in excess. The mercury sulphide is soluble in solution of sodium sulphide with formation of $\text{Hg}(\text{NaS})_2$, which, through the action of the amalgam, gives Na_2S and Hg, according to the 30 equation:

In order to avoid the formation of sodium hydroxide, it is suitable to exclude materials tending to cause decomposition of the amalgam.

Generally the reaction between amalgam and polysulphide to form the sodium sulphide is aided by thorough contact among the reagents, by increase in the temperature, by increase of the 40 quantity of sodium in the amalgam and by increase of the sulphur content in the polysulphide.

Upon the accompanying drawing is shown diagrammatically, the apparatus which may be utilized. The electrolytic cell 1 may be used for the 45 production of the amalgam while the sodium poly-sulphide may be produced in the chamber 5.

The sodium amalgam and sodium polysulphide are then caused to flow together into the reaction apparatus 2.

In the reaction chamber 2, the characteristic orange color of the polysulphide solution will be decolorized progressively as the polysulphide is converted to the sulphide.

A part of the sodium sulphide solution obtained 55 is passed into the chamber 4 where sulphur is added to it and it is then passed into the chamber 5 for reintroduction into the chamber 2.

The remaining portion of the sodium sulphide may be passed into the cooler 6 for the preparation of crystals containing 32% Na_2S or into a concentrator 7 where sodium sulphide is provided having a concentration of 62% Na_2S .

The mercury from the reaction apparatus 2 is washed in the apparatus 3 and then returned to 65 the electrolytic cell 1.

I claim:

1. The process of producing alkali metal sulphides which comprises reacting an alkali metal amalgam with an aqueous solution of the corresponding alkali metal polysulphide.

2. The process of producing alkali metal sulphides which comprises reacting an alkali metal amalgam with an aqueous solution of the corresponding alkali metal sulphide and sulphur.

3. The process of producing an alkali metal sulphide which comprises reacting an alkali metal amalgam containing a fraction of 1% of the alkali metal with an aqueous solution of the corresponding alkali metal polysulphide.

4. In the manufacture of sodium sulphide, the improvement which comprises reacting sodium amalgam with sodium polysulphide in an aqueous medium to form sodium sulphide.

5. In the manufacture of sodium sulphide, the improvement which comprises reacting sodium amalgam with the corresponding sulphide and sulphur in an aqueous medium to form additional sodium sulphide.

5
